FIRE EXTINGUISHING AND ALARM APPARATUS

Ernest A. Lowe and John R. Hamilton, Cleveland Heights, Ohio, assignors to Automatic Sprinkler Company of America, Cleveland, Ohio, a corporation of Delaware

Application September 10, 1930, Serial No. 480,900

21 Claims. (CL. 169—17)

This invention relates to improvements in fire extinguishing and alarm apparatus.

It is a primary object of the invention to provide a system which will accommodate a very large number of fire zones from one main control valve while retaining the uniformity and accuracy in operation achieved in the smaller systems.

It is a further object to provide a system of this character in which supplemental control tubing is employed and wherein the supplemental tubing and main fluid distributing pipes are at all times supervised so that any defect therein may be immediately noted.

Another object of the invention is to produce a more reliable and flexible system of protection free from the difficulties and objections found by experience to exist in those systems which like the present depend for their action upon the control of a thermostat in the fire zone exercised through a pressure responsive device at the place of operation of the main valve or other device through which the fire extinguishing medium is supplied to the fire zone by suitable piping.

To these ends the present invention comprises certain combinations of devices and elements assembled and cooperating in the manner herein-after specified and claimed.

In our improved invention we employ a pressure responsive multiple diaphragm control for a detent release mechanism associated with a means for supplying the fire extinguishing agent to the piping of the various fire zones which fire zones respectively are provided with thermal means for rendering said multiple diaphragms individually and respectively operable independently of one another by a change of pressure all as will be more particularly hereinafter described.

More specific objects relate to the improved type of control valve, heat absorbing elements and other control devices employed to make certain the operation of the main control valve under various abnormal heat conditions.

The above and other objects will appear more fully from the following description when considered in connection with the drawings in which:

Figure 1 is an elevational view, parts being in section, showing a portion of a fire extinguishing and alarm system constructed in accordance with our invention.

Fig. 2 is an enlarged sectional view taken substantially on the line 2—2 of Fig. 1.

Fig. 3 is a detailed view of the device for actuating the main gate valve alarm.

Fig. 4 is a similar view illustrating one of the heat absorbing elements.

Fig. 5 is a perspective view showing a detail of construction embodying a latch lever and weighted release lever released by movement of the latch lever in either direction due to increase or decrease of pressure within the control tubing.

Referring to the details of the drawings we have illustrated at 4 a conventional source of fluid supply such as a water supply main provided with a manual gate valve 5. A main control valve 6 is employed for supplying fire extinguishing fluid, water for example, to the main distributing pipe 8 and branch lines 10. The branch distributing pipes 10 lead to the various fire zones and are provided with normally closed sprinkler outlets 12 of any desired type and employing for instance a fusible metallic link 13 for causing the opening of the sprinkler outlets on the occurrence of certain predetermined temperature conditions adjacent the outlets.

The control valve 6 is preferably of the type wherein the main valve closure 14 or other device is normally held closed by mechanical means adapted to be tripped to release the valve when fire occurs. In the construction shown said valve closure is latched or held down in closed or normal position by means of a latch 16 mounted and operated as will be presently described. The closure is a part of, or suitably attached to, a clapper 20 which is pivotally mounted as at 21 preferably within the valve body. The clapper 20 is employed as an air clapper to prevent the escape of air under pressure from the distributing pipes while the system is in a normal unoperated condition. To this end it is provided with a special design of flexible valve facing as indicated at 24, this facing being U-shaped in cross section and opening outwardly whereby the upper side of the U is received within a pocket or circular recess in the valve clapper 20 and the lower flexible or extensible side of the U receives the pressure of the fluid such as air from the distributing pipe bears against the stationary valve seat 26. Pressure of the air or other fluid entering the open side of the facing tends to expand the lower side or flexible edge of the U against the valve seat 26 and prevent loss of any air from the distributing pipes 8 to the chamber 15 between the two valve clappers.

Loss of air from the pipe 8 past the air clapper may be further prevented by a water seal as usual in the art maintained in the space above the air clapper as indicated and admitted there-

to from a suitable priming cup or reservoir 23 through the valve 23'.

Valve or closure 14 is provided with a gasket 17 fastened to a projecting lip or edge thereof in position to engage by its inwardly projecting flexible edge with the valve seat on which the valve normally engages for preventing the passage of water or other medium from pipe 4 to pipe 8. As will be seen the pressure of said medium from the supply 4 is, by this construction, permitted to enter the free space above the flexible lip or edge of gasket 17 and to act thereon to press said flexible edge down firmly upon the valve seat.

The latch 16 is carried by a weighted operating arm 30 pivoted at 28 at any suitable point and a sealing gasket 32 on the arm 30, of substantially the type indicated at 24 is provided for closing the opening 33 through which the arm extends when the latch is in unlatched condition.

In this position the pressure of water in the chamber 15 serves to compress the lower side of the U against the valve seat surrounding the opening 33 and prevent loss of water and water pressure when the apparatus is in operation.

The weighted lever 30 is normally retained in its latching position with the valve 14 closed by means of a pivoted lever 34 pivotally supported from a wall 36 of a compensating chamber 38 to be presently described. Said lever 34 is mounted within one or more flexible rubber bushings 36' supported on the wall of the chamber, said flexible members being of proper construction to seal said compensating chamber at the points of attachment thereto and prevent escape of air therefrom. A lug or detent 30' on the end of the weighted lever 30 engages normally with a shoulder or detent on the end of lever 34 but when the lever 34 is depressed the arm 30 is disengaged and drops under the influence of its weight so as to release detent 16. Other sealing devices may be substituted for the member 36' shown. The lever 34 suitably connected with or within the compensating chamber 38 is formed with or has attached thereto an elongated transversely extending bar 40 located in position to be engaged by any one of a plurality of weighted release levers 42, one of which corresponds to each of the various fire zones.

Each separate fire zone or group of a few fire zones is provided with an individual control system comprising supplemental tubing 44, hollow heat absorbing elements 46, (one or more) connected with the tubing, diaphragm casing 47 to which the tubing is joined and a flexible diaphragm 48 connected to a latch lever 50 by means of link 51 for controlling its individual weighted release lever 42. The casings 47 and diaphragms 48 are positioned in the chamber 38 in which a specific pressure condition is maintained, each supplemental tube being provided with a restricted opening 49 employed for the purpose of equalizing the pressure in the various tubes and chamber 38 and accommodating slow increases or decreases of pressure in the chamber 38 or supplemental tubes 44 and heat absorbing elements 46 where such changes are of a character that does not indicate the presence of a fire condition. The latch levers 50 employed for controlling the levers 42 are provided as shown more particularly in a perspective in Fig. 5 with right-angled extensions 52 engaging with a horizontal extension comprising a lug or detent 42' on lever 42 (Fig. 2) so that either an increase or decrease of pressure within the tubing 44 and casings 47, relatively to the pressure in chamber

38, will release the levers 42 and ultimately open the main control valve.

The heat absorbing elements 46 for producing the pressure to actuate the diaphragms 48 of each of the individual control units is provided with devices actuated on the occurrence of relatively low but abnormal heat condition for uncovering a relief opening through which the air or gas under the maintained tension in the container, comprising the heat absorbing elements 10 and/or tubing associated therewith, may freely escape. If, as in the present embodiment, the maintained tension is greater than atmospheric pressure the free escape of the air through the relief opening will allow the double-acting detent 52 to rise and free the corresponding lever 42.

The automatic uncovering of this opening by a change of temperature may be accomplished in various ways. In the present instance the result is attained by providing on the element 46 (Fig. 4) a tubular extension 54 which may be normally closed by means of the cup-shaped member 56 which contains a quantity of fusible material 57 which normally retains the cup and material 56 in position to close the interior of the units 46 from the outside air. Torsion springs 58 are attached to the body of the elements 46 and engaged with the cups 56, the springs being tensioned slightly when the cups are in their normal 30 positions so that when the material 57 fuses the cup and the main body of the material 57 will be drawn clear of the projection 54 of the heat unit to permit equalization with the outside air and the subjection of the interior of the tubing 35 to atmospheric pressure with the consequent unlatching of a lever 42 and the opening of the main control valve. The members 56 are in effect flags or signals to indicate at a glance whether the tubing is sealed or opened to the atmosphere 40 at these points, the open position of the members, indicated in dotted lines in Fig. 4, being readily distinguished from the closed position.

In order that an attendant may be notified of the operation of any of the levers 42 an annunciator is employed which is provided with an operating coil and a visual element or flag for each lever 42. As shown the annunciators each include a setting coil 60 (Fig. 2) and a visual signal element 62. The circuits to the coils 60 include the battery or other source of current supply 63, switch contact member 64, operated by the levers 42 when the latter fall, and if desired an alarm bell, as shown, actuated when any coil 60 is energized.

Likewise when the main control latch lever 30 is released and drops down to position to release the valve closure 14 the weighted lever engages a switch 66 for closing the circuit to an alarm 68 to indicate at any time the release of the lever 30.

The system contemplates the complete supervision of the supplemental tubing 44 and distributing pipes 8 and 10. A pressure condition slightly different from atmospheric condition is therefore maintained in the main distributing pipes and supplemental tubing. As shown the interiors of the chamber 38 and distributing pipes 8 are connected by tubing 70 and 72 to the pressure supply pipe 74, one way valves 76 and 78 being provided for the tubes 70 and 72 to prevent the escape of air or water pressure from the chamber or pipes into one another or back into the supply tube 74. The specific devices shown maintain air pressure in the supplemental tubes 75

and distributing pipes and may be of any usual type. As shown they comprise a U-shaped pipe 76 one leg 78 of which forms an air chamber wherein air and liquid separate by gravity and the other leg 79 of which constitutes a vertical liquid column for supplying the desired pressure in the system. Air is added to the chamber 78 by means of the inspirator 80 which receives liquid through the small pipe 82 controlled by the valve 83. The flow of water through the restricted portion of the inspirator 80 draws air through the tube 84 and one-way valve 85 into the chamber 78 where the air and water separate by gravity and the water level in the leg 78 is gradually reduced and the pressure correspondingly increased.

The automatic action of the inspirator or pump is brought about in the present instance by the following devices which cause the normally closed valve 83 to be opened when the pressure in the system decreases to a predetermined extent.

The stem 89 of the valve 83, sealed by the diaphragm 89a or otherwise, is controlled by the pivoted lever 90 formed with projections 91 engageable by a weighted pivoted lever 92 when the latter is moved respectively to one side or the other of its pivot. The connection between the lever 90 and valve stem 89 may be a pin and slot connection in order to give a sudden movement to the valve 83.

The weighted lever 92 is controlled in its movement by the pressure within the chamber 78, pipes 74, etc. which pressure is transmitted through suitable tubing 93 to the flexible diaphragm 94 connected to one end of a pivoted weighted lever 95 formed with a projecting arm connected by a suitable link to the lever 92 so that corresponding movements of the lever 95 are transferred to the levers 92 and 90.

It will be understood that a decrease or increase in pressure in the chamber 78 and tubes 74 connected to the distributing piping and supplemental tubing will be transmitted to the diaphragm 94 for controlling the position of the levers 95, 92 and 90. On a decrease of pressure within the diaphragm 94 the lever 95 is rocked in a clockwise direction thus moving the lever 92 counterclockwise, the lever 92 engaging lever 90 at the left side of its pivot and opening valve 83 to cause the actuation of the inspirator. The reverse action takes place on an increase of pressure thus resulting in a closure of the valve 83.

In order to give a suitable warning if the air pressure within the system should fall below a predetermined or normal pressure condition which it is desired to maintain therein by the automatic action of the pump, a pressure responsive device responsive only to decrease of pressure below that which brings the pump into operation is employed. For this purpose a similar collapsible and expansible member 96 may be used which is normally held distended by the pressure communicated thereto from the pipe 93 and which collapses when the pressure falls below that for causing the actuation of the bellows 94 and lever 95. The diaphragm 96 engages with a projection on the weighted lever 97 for causing the latter to fall on decrease of pressure sufficient to collapse bellows 96. Lever 97 is arranged to strike and open valve 98 for admitting water from the pipe 82 to the branch pipe 99 for actuating the water motor alarm 100.

It is desirable to notify the attendant at any time the main gate valve 5 is closed. This may be accomplished in the embodiment shown by

providing the manual operating member 102, employed for controlling the main gate valve, with a projection 103 engageable with the free end of a pivoted lever 104 for opening the valve 105 whenever the control wheel 102 is turned to the right to close the gate valve. Valve 105 is normally held closed by the water pressure and when opened it is retained in this position by means of the latch lever 106 until manually released. Water is thus admitted from the water main 4 through the tube 108 for actuating the water motor alarm 100.

It is desirable also to give an alarm whenever the main control valve 6 is open. This may be accomplished by means of pipe 112 leading from valve chamber 15 to the fire gong or alarm 110 as shown.

By means of the above described devices we have provided a system wherein on the occurrence of a normal fire and the development of heat and pressure at the elements 46 one or more of the weighted levers 42, individual to each fire zone, are released causing the opening of the main valve and the creation of an alarm. Since each control unit is individual to each fire zone 25 the thermostatic action is positive in that none of the actuating pressure can pass to other control pipes or chambers connected therewith except by way of the restricted leaks provided to accommodate small pressure changes. If the heat developed is not of sufficient intensity to actuate the diaphragm 48 and release the lever 42, or, in other words, if the restricted vent 49 accommodates the increase of pressure so that the diaphragm is not actuated then on the occurrence 35 of a relatively low but sustained abnormal condition of heat that advances to a predetermined degree one or more of the closures or caps 56 are withdrawn from the elements 46 due to the fusing of the material 57 and atmospheric pressure is admitted to the supplemental tubing. This causes a substantial change in pressure in the tubes 44 and the immediate inward movement of a diaphragm 48 resulting in the release 40 of the main valve closure 14. Fire extinguishing 45 fluid is thus made available at the outlets 12 in advance of the opening of the sprinkler outlets. In any event water damage is avoided except on the occurrence of an actual fire due to the use of fuse controlled outlets. If at any time a rupture occurs in the supplemental tubing or main distributing pipes such that the inspirator cannot maintain the desired pressure therein this is made evident by the ringing of the alarm 100 so 50 that the attendant is notified to correct the defect. 55

While in the foregoing specification we have referred to the supervisory pressure in the piping 8, 10, tubing 44, and heat absorbing devices 46 as a plus pressure, that is, a pressure above atmosphere, it will be obvious to those familiar with this art that means may be provided for maintaining a minus pressure, that is, below atmosphere, in the said piping, tubing and heat devices, 65 the said minus pressure being used as the supervisory means. We accordingly desire to be limited in this respect only by the confines of the following claims.

Having now described our invention, we claim: 70

1. In a fire extinguishing system, a system of fire extinguishing fluid distributing pipes, release means for supplying fire extinguishing fluid to said pipes, temperature responsive devices for actuating said release means, said devices in- 75

- cluding a heat absorbing pressure producing element in a fire zone, an element responsive to pressure changes operatively associated with said release means and with said heat absorbing element and means responsive to a predetermined heat condition for permitting the equalization with atmosphere of any pressure in said elements.
5. In a fire extinguishing system, a system of fire extinguishing fluid distributing pipes, release means for supplying fire extinguishing fluid to said pipes, temperature responsive devices for actuating said release means, said devices including a heat absorbing pressure producing element in a fire zone, an element responsive to an increase or decrease of pressure and operatively associated with said release means and with said heat absorbing element and means responsive to a predetermined heat condition for permitting the free passage of pressure between said devices and an outside space.
6. In a fire extinguishing system, a system of fire extinguishing fluid distributing pipes, release means for supplying fire extinguishing fluid to said pipes, temperature responsive devices for actuating said release means, said devices including a heat absorbing pressure producing element in a fire zone, an element responsive to an increase or decrease of pressure and operatively associated with said release means and with said heat absorbing element, means for normally maintaining a pressure other than atmospheric pressure in said heat absorbing element and pressure responsive element and means responsive to a predetermined heat condition for permitting the free passage of pressure between said devices and an outside space.
7. In a fire extinguishing system, fluid supply means, release means for supplying fluid to said fluid supply means, a system of tubing provided with pressure producing devices in a fire zone, pressure responsive devices operating said release means on a relatively sudden occurrence either of atmospheric pressure or of pressure substantially greater than atmospheric pressure in said tubing, means for normally maintaining in said tubing a pressure other than atmospheric pressure and means in said fire zone, responsive to a predetermined heat condition for suddenly subjecting said tubing to atmospheric pressure and actuating said fluid supply means thereby.
8. In a fire extinguishing system, fluid supply means, release means for supplying fluid to said fluid supply means, a system of tubing provided with pressure producing devices in a fire zone, and with pressure responsive devices operating said release means on occurrence of a relatively sudden increase or decrease of pressure in said tubing, means for normally maintaining in said tubing a pressure other than atmospheric pressure and supplemental means for suddenly changing the pressure in said tubing on the occurrence of a predetermined heat condition adjacent said pressure producing devices and actuating said fluid supply means thereby.
9. In a fire extinguishing system, a source of fluid supply, fluid distributing pipes extending to a fire zone, valve means for controlling the admission of fluid from said source to said pipes, a normally closed sprinkler outlet for said pipes operable on the occurrence of a relatively high heat condition in a fire zone, a system of supplemental tubing containing a pressure conveying fluid and normally subjected to the heat condition adjacent said outlet, a pressure responsive device controlled by the pressure generated by heating
- of the fluid in said tubing, means for maintaining pressure other than atmospheric pressure in said pipes and supplemental tubing, means actuated by said pressure responsive device for actuating said main valve on an increase of pressure in said tubing or on subjecting said supplemental tubing to atmospheric pressure, means responsive to the subjecting of said pipes to atmospheric pressure for creating an alarm and means for subjecting said supplemental tubing to atmospheric pressure on the occurrence of an abnormal heat condition and less than that required to operate said sprinkler outlet.
10. In a fire extinguishing system, means for supplying fire extinguishing fluid thereto, control means therefor including a system of control tubing containing a fluid under pressure other than atmospheric pressure and associated heat absorbing, pressure producing element and a pressure responsive device responsive to an increase or decrease of pressure and operatively associated with the control means, said heat absorbing element including a fusible closure for subjecting the interior of said element and tubing to atmospheric conditions on the occurrence of an abnormal heat condition.
11. In a system of the type described, control means responsive to changes of pressure in a confined body of air or gas greater than a predetermined rate when occurring through change of thermal conditions affecting said body of air or gas combined with means for venting the confined body of said air or gas upon the attainment of a fixed temperature irrespective of the rate of change.
12. The combination with a fire extinguishing apparatus, of a control means comprising a flexible member and a detent device operating by either an increase or a decrease of pressure on said flexible member, a pressure conveying tube containing a confined body of pressure conveying fluid at other than atmospheric pressure and adapted to convey pressure to said member, heat collecting chambers or containers connected with said tube, a restricted compensating vent and casting in communication with a face of said flexible member opposite that on which pressure in said tube acts, said vent being connected to said casting for predetermining an effective rate of increase of pressure that will be effective to operate by increase of pressure on said flexible member upon change of temperature affecting the heat condition of the confined body of air or gas and means responsive to increase of temperature to a fixed or ultimate degree irrespective of the rate of change of temperature for opening a vent for the confined body of air or gas to actuate said control means.
13. The combination with air or gas tubing and a heat collecting chamber connecting therewith for producing increase of pressure in said tubing, of a fuse controlled seal for said chamber adapted to vent the same on the attainment of a predetermined or ultimate temperature.
14. In a system of the type described, thermally responsive controlling means comprising a container of air or gas maintained at a definite pressure, pressure operated means capable of operating on decrease in pressure and responsive to a change of the pressure of said air or gas at a predetermined rate of increase produced by heating of the air or gas and means for venting said container and thermally controlled and operating automatically upon the attainment of a fixed or definite temperature attained irrespective of

the rate of rise of temperature to permit the free entry or escape of air.

12. In a system of the type described, thermally responsive controlling means comprising an enlarged heat collecting chamber of air or gas and tubing connected therewith and leading to a pressure operated means capable of operating on decrease in pressure, said pressure operated means being responsive to a change of the pressure of said air or gas at a predetermined rate of increase produced by heating of the air or gas and means for venting said chamber and thermally controlled and operating automatically upon the attainment of a fixed or definite temperature attained irrespective of the rate of rise thereof to permit the free entry or escape of air.

13. In a system of the type described, thermally responsive controlling means comprising a container of air or gas maintained at a predetermined pressure greater than that of the atmosphere, pressure operated means responsive to change of said pressure, a double acting detent responsive to either an increase of said pressure produced by heat or to a decrease and means thermally controlled for venting said container.

14. In a system of the type described, thermally responsive controlling means comprising a container of air or gas maintained at a definite pressure, pressure operated means responsive to a change of the pressure of said air or gas at a predetermined rate of increase produced by heating of the air or gas and an automatic fuse controlled vent operating upon the attainment of a fixed or definite temperature attained irrespective of the rate of rise of temperature to permit the free entry or escape of air.

15. In a fire extinguishing system for a plurality of fire zones, distributing piping for distributing fluid to the fire zones, outlets for said piping, means for controlling the admission of fluid to said piping, a plurality of individual control devices for controlling said means and each including a temperature responsive pressure producing element in a fire zone, a pressure responsive element and a release element actuated thereby, a closed casing enclosing all of said release elements and pressure responsive elements, restricted means for causing said pressure responsive elements to communicate with the interior of said casing and means for operating said fluid controlling means on actuation of any of said release elements.

16. In a fire extinguishing system for a plurality of fire zones, distributing piping for distributing fluid to the fire zones, outlets for said piping, means for controlling the admission of fluid to said piping, a plurality of individual control devices for controlling said means and each including a temperature responsive pressure producing element in a fire zone, a pressure responsive element and a release element actuated thereby, a closed casing enclosing all of said release elements and pressure responsive elements, restricted means for causing said pressure responsive elements to communicate with the interior of said casing and means comprising a master lever having a portion extending within said casing for cooperation with any of said release elements and a portion extending without the same for operating said fluid controlling means on actuation of any of said release elements.

17. In a fire extinguishing system for a plurality of fire zones, distributing pipes for conducting fluid to said fire zones, a control unit

for each fire zone, each unit including a pressure producing and a pressure responsive element connected by tubing, means actuated by said pressure responsive element of any of said units for controlling the flow of fluid to said pipes, a pressure chamber and restricted means of communication extending from the interior of each of said units to said chamber.

18. In a fire extinguishing system for a plurality of fire zones, means for controlling the admission of fluid to the various zones, said means comprising a plurality of units, each unit including a pressure producing element in a separate fire zone, a pressure responsive device formed with a pressure operated movable element having opposed faces with one of said faces communicating by tubing with said pressure producing element, an individual release member associated with each of said movable elements, means for normally maintaining pressure against both faces of said movable element, restricted means for equalizing the pressure on the opposite faces of said movable elements and means controlled by any of said individual release members for supplying fluid to said system.

19. In a fire extinguishing apparatus the combination of means for supplying fire extinguishing medium of a weighted control latch lever therefor, a retaining device normally maintaining said latch lever in latching position, a series of weighted release levers each adapted when released to engage and actuate said retaining device for the purpose of freeing said latch lever, individual pressure responsive diaphragms adapted to control and release said release levers respectively and individual and independent pressure conveying tubing for conveying pressure operating on said diaphragms, said tubings being respectively connected to thermally responsive pressure producing devices located in different fire zones and said tubings for different zones each extending into a zone different from those into which the other tubings extend and terminating in a common air inclosure wherein it is provided with a restricted leak and adapted each to create a difference of pressure on each individual diaphragm without substantial interference in its action from the presence of other diaphragms.

20. In a fire extinguishing system for a plurality of fire zones, distributing pipes for distributing fire extinguishing fluid to said zones, supply means common to said zones for supplying said fluid thereto, temperature responsive means for controlling said supply means, said temperature responsive means consisting of a plurality of units each formed with a heat absorbing pressure varying element in a fire zone different from the fire zones for other units, a pressure responsive element for each unit responding to air pressure conveyed thereto through tubing, connections independent of and disconnected from the tubing for other units so that the change of pressure generated in the tubing of any unit will not be dissipated in the tubings for other of said units, a release lever for each unit and a common release means actuated in response to the actuation of any of said release levers for bringing said supply means into action.

21. The combination with a fire extinguishing apparatus, of a control device responsive to either an increase or decrease of pressure in a confined body of air or gas including heat collecting means

the operation of the same by increase of pressure being on the principle of rate of rise of pressure thermally produced by said heat collecting means and means for venting the confined body of air or gas on the attainment of a fixed or ultimate temperature and irrespective of

the rate of rise of pressure by thermal action, said venting being operative to produce action of the control device by decrease of pressure.
